UNITED STATES PATENT OFFICE.

EDWARD B. LEMON, OF MILWAUKEE, WISCONSIN.

SAFETY FEEDING DEVICE FOR CLOTHES WRINGERS.

Application filed April 26, 1924. Serial No. 709,107.

Power operated clothes wringers have attained great popularity in household laundries, and are now in general use. Feeding the fabrics between the compression rolls of 5 such wringers is a very particular operation and is frequently attended with injury to the fingers and hand of the operator, due to being caught and drawn between the rolls, despite her most watchful care.

10 The purpose of the present invention is the production of a feeding device for attachment to clothes wringers which will obviate the liability of the fingers of the operator being caught between the rolls, such feeding device being so formed as to receive the 15 fabric and carry it to a point where it will have frictional engagement with the rolls and be drawn between them in the rotation of the latter.

20 The feeding device is embodied in a pivoted bar which is provided on its forward side with an elongated wedge-shaped portion, for entering the fabric between the rolls, and on its tapering sides with fixed 25 protuberances which latter are designed to support the fabric somewhat clear of the bar, so that the fabric may be drawn between the rolls without dragging, thus greatly facilitating the movement of the wet fabric over 30 the bar without material frictional resistance. Also it is the function of the said protuberances, by engagement with the rolls, to restrict the movement of the wedge-shaped portion into the space between the rolls.

35 The novel features of the invention will now be particularly described, and then pointed out in the appended claims.

40 In the consideration of this specification, reference is to be had to the accompanying drawing which shows a simple constructional form in which my invention has been embodied. In such drawing:

45 Figure 1 is a plan view in the horizontal plane which extends between the rolls of the wringer, and showing the manner of the attachment of my improved safety feeding device to the frame, the latter being transversely sectioned.

50 Fig. 2 is a vertical sectional view, enlarged, on the line 2—2, Fig. 1, looking in the direction of the arrows, and showing the manner in which my improved device operates.

55 Fig. 3 is a view in front elevation of the central section of the bar embodied in the

construction of my feeding device, and showing the wedge-shaped formation of the fabric feeding element, together with the arrangement of the fixed protuberances on the tapering sides thereof which provide a clearance between the bar and the fabric resting thereon.

In the drawing, the numerals 10 and 11 indicate the standards of a clothes wringing machine, in which standards the shafts 12 and 13 of the rolls 14 and 15, are journaled in the manner usual to constructions of this kind.

A bracket 16 is attached to the standard 10, such bracket receiving and supporting 70 pivotally one end of a feeding bar 17, the latter being provided at its free end with a projection 18, or other formation, for engagement by one hand of the operator, and by means of which the bar may be turned on its pivot to swing the said bar toward and away from the wringer rolls during the operation of the machine.

Upon its forward face and near its central length, the bar 17 is provided with a longitudinal and lateral projection 19, in the form of an elongated wedge, the edge of which is adapted to enter the open space existing at the front side of the rolls and in the plane of their peripheral contact. In the movement of the bar 17 toward the rolls, the wedge-shaped projection 19 is designed to penetrate the said open space to an extent that the tapering sides of the wedge will lie closely adjacent the surfaces of the rolls, but not in contact therewith, so that the said wedge cannot, accidentally or otherwise, exert a separating action upon the said rolls.

I achieve this restriction in the forward movement of the bar 17, by the provision upon the bar of means for engaging the rolls at points remote from the line of their peripheral contact, so that such forward movement of the bar is arrested at the desired point, and no wedging action can take place.

The means referred to are constituted as a plurality of fixed enlargements or raised protuberances 20 on the tapering sides of the wedge-shaped portion of the bar 17. The protuberances 20 are rounded upon their exterior surface, and extend outwardly from the sides of the wedge, so as to provide a clearance between the sides of the wedge and the rolls. And although they function in

the manner hereinbefore described, they have the further important function of supporting the fabric clear of contact with the sides of the wedge, so that the wet fabric, when 5 grasped by the rolls, may be drawn off the bar without dragging over the sides thereof. Thus, the feeding movement through the rolls is effected without imposing delicate fabrics to any unusual strains, so that damage thereto is avoided.

The bar 17 with the fixed, rounded protuberances 20 is cast as a single piece, and machining thereof for the reception of other adjunctive parts is obviated. Preferably, 15 the casting is of aluminum, but may be of any suitable material. It is advantageous that it be non-corrosive. In the interest of lightness, I cast the wedge-shaped section with a hollow rear portion, as indicated at 20 21. My construction is very economical in cost, and may easily be attached to any existing machine.

In operation, the rolls are set in motion, and the bar 17 is swung outwardly from the 25 rolls by one hand of the operator. The wet fabric from the tub is then passed vertically into the widened space between the rolls and the bar, and laid over the latter as the bar is moved toward the rolls. When the fabric 30 contacts with the rolls under the pressure exerted by the wedge-shaped portion of the bar, the frictional engagement of the rolls with the fabric will draw the latter from the bar and pass it through the rolls, whereby 35 the moisture is expressed from the fabric. The wet fabric will not cling to or drag over the sides of the wedge-shaped portion of the bar, for the fixed protuberances 20 create a clearance which facilitates the movement of 40 the fabric. The fingers of the operator are

never near the rolls, and consequently liability to injury is avoided.

Having thus described my invention, what I claim and desire to secure by Letters Patent of the United States, is:

1. As a new article of manufacture, a safety feeding device for clothes wringers constituted as a bar provided with means for pivotally supporting it at one end, and hand-engaging means at the other, whereby 45 the said bar may be swung in a horizontal plane upon its pivotal support, the said bar being provided upon its forward side with a wedge-shaped portion, for entering the fabric between the rollers, and the tapering 50 sides of which wedge-shaped portion are provided with fixed protuberances, which latter support the fabric clear of the wedge-shaped portion to facilitate its passage thereover; and also prevent engagement of 55 the wedge-shaped portion with the rollers.

2. As a new article of manufacture, a safety feeding device for clothes wringers constituted as a bar provided with means for pivotally supporting it at one end, whereby 60 the said bar may be swung in a horizontal plane upon its pivotal support, the said bar being provided upon its forward side with a wedge-shaped portion, for entering the fabric between the rollers, and the tapering 65 sides of which wedge-shaped portion are provided with fixed protuberances, which latter support the fabric clear of the wedge-shaped portion to facilitate its passage thereover, and also prevent engagement of the 70 wedge-shaped portion with the rollers.

In testimony whereof, I have signed my name at Milwaukee, this 21st day of April, 1924.

E. B. LEMON.
